Russell Mann of Troy, N.Y.
Assignor to
George W. Eddy of Waterford, N.Y.
Letters Patent No 714 Dated July 3rd 1855

The Schedule referred to in these Letters Patent and making
part of the same.

To all whom it may concern

Be it known that I, Russell Mann
of Troy in the County of Rensselaer and State of New York
have invented or produced, a new and original design of
Cook Stove which I call the "North Star" and I do hereby
declare that the following is a full, clear and exact
description of the same, reference being had to the annexed
perspective drawing with the letters of reference marked
theron, forming a part of this Specification.

The description of my design of Cook Stove
is as follows viz: A is the top plate, with the moulding
(a) arranged around the edge. B is the front plate having
the raised panel and damper drop door, with the moulding
(b), and center raised panel (C). C.C. are the front doors
which have upon their panels the lozenged shaped or-
naments D.D. with their surfaces cut to represent rays

(d) (d) are corner ornaments on the panel, the doors have their edges finished with the mouldings (e.e.) E is the bottom plate with the moulding (f) arranged around its edge. F is the damper plate, G is the jamb plate, with the moulding (g) around its edge, and the scroll panel (h) at the top. (i i) are series of lozenge shaped ornaments, disposed on the panel of the jamb, H, H, are the oven doors, having the lozenge shaped ornaments I, I, arranged upon the panels, and also the corner ornaments (j j) (k) is a moulding around the edges of the doors, T is a leg, having the lozenge shaped ornament (l) upon its face.

Having described my design of Cook Stove. What I claim as new and desire to secure by Letters Patent is; the ornamental design and configuration of stove plates such as herein described and represented in the annexed drawing.
